AUTOMATIC CONTROL OF INSPIRATORS FOR GAS PLANTS

Filed Nov. 3, 1947

UNITED STATES PATENT OFFICE

2,608,477

AUTOMATIC CONTROL OF INSPIRATORS
FOR GAS PLANTSDavid W. Shaeffer, St. Louis, Mo., assignor to
Phillips Petroleum Company, a corporation of
Delaware

Application November 3, 1947, Serial No. 783,661

4 Claims. (Cl. 48—180)

1

This invention relates to gas air inspirator systems. In one of its more specific aspects it relates to an electrically operated and fully automatic gas air inspirator system.

One object of my invention is to provide an electrically operated and fully automatic gas air inspirator system. Another object of my invention is to provide an electrically operated and fully automatic gas air inspirator system which continues to function even during periods of electric power failure. Still another object of my invention is to provide an electrically operated inspirator system, which during times of electric power failure, continues in smooth and uninterrupted operation.

Electrically operated inspirator systems are relatively simple to construct and operate and the operation of such systems is very easy to control. However, in case of electric storm when the electric power is interrupted or when power is cut off for any reason whatever, such inspirator systems as now in operation cease to function. I have devised an inspirator system which, as mentioned hereinbefore, is adapted to continue operation even during periods of electric power failure.

The figure illustrates diagrammatically one form of apparatus in which to carry out the improved method of my invention. Referring to the figure, reference numeral 1 refers to the gas or liquified gas storage tank which contains gas to be inspirated. Gas from the storage tank 1 passes by way of a pipe 1a, a valve 3 and a pipe 2 to a pressure reducing valve 4. From this valve the gas continues passage through line 2, a valve 5, a line 8, a line 9 and a valve 10 to a second pressure reducing valve 11. From this valve the gas continues passage on through a line 9, a valve 12, some pipes 16 and 31, a pipe 28, some valves 29, 27 and 30. From pipe 28 the gas passes then through a pipe 34 into a manifold 35 which distributes the gas through some individual lead pipes 34a, 37, 39 and 41 through some valves 36, 38, 40 and 42, respectively, into several units of the inspirator system. Reference numerals 43, 44, 45 and 46 refer to some solenoid operated on-off valves. From these solenoid operated valves gas passes into the respective inspirators 47, 48, 49 and 50. From these inspirators the gas air mixture or mixtures pass through some manually operated valves 51, 52, 53 and 54 into a manifold line 55 which then delivers the entire gas air mixture to a gas main 56 which in turn may lead to a run storage tank, not shown, or to a distribution system or appliance, also not shown.

Electric power from a source, not shown, is con-

2

ducted to my inspirator system through wires 66 and 66a. These wires connect with a pressure operated multiple controller switch unit 65. From this unit 65, some lead wires 60, 62 and 64 are connected directly with the solenoid valves 45, 44 and 43 respectively. Some return wires 59, 61 and 63 from these three solenoids are connected to a common return wire 68 which in turn is connected with one side 66a of the power line. To this return wire 68 is also connected a return wire 57 from the solenoid valve 46. The other wire 58 from this solenoid valve 46 is directly connected to the source of power wire 66. The wire 57 passes through one portion of a signal assembly 71 and through the electrical switch portion of a pressure operated electrical switch 69. From this pressure operated switch, a pipe 70 leads to the gas main 56.

Also from the pressure operated multiple controller switch 65 a pipe 67 leads to the gas main 56. Pipe 7 and valve 6 serve as a bypass around the pressure reducing valve 4, and pipe 14 and valve 13 serve a similar purpose around the pressure reducing valve 11. In a like manner, pipe 32 and valve 33 form a bypass around the valve 27. From pipe 31 a pipe 17 leads to a pressure reducing valve 18, the downstream side of which is connected to a pipe 19 which carries a restricting orifice 20. On the downstream side of the orifice 20 a pipe 24 leads to the underside of the motor 26 of a motor regulator valve assembly 25. This assembly consists of the motor 26, a valve 27, which are connected by a valve stem 21.

To the downstream end of pipe 19 is connected a valve 23 which is a back pressure regulator type of valve. From this valve pipe 22 leads to the gas main 56.

The pressure reducing valves 4, 11 and 18 are of the constant pressure outlet type of valve, and in operation valve 4 is intended to reduce the gas from its storage tank pressure to about 50 pounds per square inch. Valve 11 is intended to reduce the pressure from this 50 pounds to about 25 pounds while the valve 18 is intended to reduce the pressure from 25 pounds to that of an 18 inch column of water.

Low pressures in such systems, that is, pressures of a few ounces per square inch are frequently measured and expressed in terms of inches of a column of water, for example, the 18 inch water column pressure above mentioned means the pressure exerted by a column of water 18 inches high.

The motor regulator valve assembly 25 is of the zero governor throttle type and is intended to

throttle the flow of gas through valve 27 or to shut off entirely valve 27 in response to gas pressure in pipe 24.

The solenoid operated on-off valves 43, 44 and 45 are of a type that when electric current is flowing through the solenoids, the valves are held fully open, and conversely when the electric current is not flowing through these solenoids, the valves automatically close. The solenoid operated on-off valve 46 is like the other solenoid valves excepting it operates in exactly the reverse manner, when the electric current is flowing through wires 57 and 58 the solenoid holds valve 46 closed and when electricity ceases to flow through wires 57 and 58 from any cause whatever, the valve 46 opens.

The pressure operated multiple controller switch 65 is standard equipment and may be purchased from instrument supply houses. This pressure switch 65 operates in response to gas pressure in the main 56 and as pressure in the main 56 decreases, the valve 43 opens, when pressure in 56 decreases further the valve 44 also opens and similarly upon a still further decrease in main pressure the third valve 45 opens.

In the operation of my apparatus, the valves 6, 13 and 33 are normally closed so that gas to be inspirated will be forced to pass through the regulators 4, 11 and valve 27 and accordingly high pressure gas such as propane from the storage tank will flow through line 1a at tank pressure to the regulator valve 4. This valve reduces the pressure on the propane to a 50 pound discharge pressure. This 50 pound propane then continues through line 2, line 8, line 9 to valve 11. On passing through this valve the pressure on the propane is reduced to a constant outlet value of about 25 pounds per square inch. This 25 pound propane then flows on through line 9, valve 12, through pipes 31 and 28. In normal operation, the motor valve 27 is fully open and the propane of 25 pounds pressure or approximately at that pressure passes on through valve 30 and line 34 to the manifold 35. From the manifold 35 the propane passes through the inspirators 47, 48 and 49 depending upon the gas requirements of the system. In one case in which a system was designed for a maximum demand of 2000 cubic feet per hour output, the inspirator 47 was of such size as to have a capacity of 500 cubic feet per hour, inspirator 48 had a capacity of 1500 cubic feet per hour, inspirator 49 had a capacity of 2000 cubic feet per hour. The standby inspirator 50 had a capacity of 3000 cubic feet per hour. Thus with a normal maximum demand of 2000 cubic feet per hour, inspirators 47 and 48 could carry the load. When demand exceeded 2000 cubic feet per hour, then inspirator 49 would turn on in response to a predetermined drop in gas main pressure. With this inspirator 49 in operation the total output of the three inspirators was 4000 cubic feet per hour and this large output would soon raise the pressure in the gas main to such an extent that the controller switch 65 would operate to close the solenoid operated valve 45.

In like manner, when the valves 43 and 44 were open and permitting the production of about 2000 cubic feet of gas per hour and if the load on the gas main dropped from any reason whatever, pressure in the main of course increased and this increase in pressure would be transmitted through pipe 67 to the controller switch 65 to close off the valve 44 for such a length of time until the gas main pressure dropped sufficiently to open the valve 44 again.

The three inspirators 47, 48 and 49 as controlled by the solenoid valves 43, 44 and 45 respectively are intended to operate electrically during all times while electric current is available. However, when electric current fails the solenoid operated valves 43, 44 and 45 are so designed that they snap shut and accordingly they do not permit uncontrolled flow of gas through the inspirators.

The solenoid operated valve 46 is normally held closed while current is flowing through the solenoid and this valve is so constructed that when the flow of current is interrupted the valve snaps open and accordingly permits flow of the propane from manifold line 35 through pipe 41, through valve 42, valve 46 and through the inspirator 50. This inspirator 50 may be of a 3000 cubic feet per hour capacity so that it can more than satisfy the normal maximum demand on the system. Discharge from the inspirator 50 flows through valve 54, the manifold line 55 into the gas main 56. Since the valve 46 is of the fully opened or fully closed type, when it is open pressure in the gas main usually builds up quite rapidly if the demand on the system is less than 3000 cubic feet per hour. I have devised a throttling control for use under such conditions so that the pressure in the gas main will not continue to increase to such an extent as to rupture pipes or otherwise create hazards. The throttling action mentioned is accomplished by the operation of the zero governor valve assembly 25. In normal plant operation if the gas pressure in the main 56 is intended to be a maximum of about 6 inches of water column (W. C.), when the pressure in the main exceeds 6 inches water column very slightly the back pressure regulator valve 23 operates to close partly. This partial closing of valve 23 causes the pressure on the downstream side of orifice 20 in line 19 to increase somewhat and this increase of pressure is transmitted through pipe 24 to the underside of the diaphragm in the motor 26 and this increase of pressure on the diaphragm operates to close partly or throttle the valve 27. In this manner the propane reaching the valve 27 leaves this valve at a pressure less than 25 pounds per square inch. And at a pressure lower than 25 pounds per square inch less propane flows through manifold line 35 and through the solenoid valve 46 and inspirator 50 and accordingly pressure in the gas main 56 drops. These several apparatus parts, that is, control valve 23, the zero governor 25, cooperatively operate to maintain a desired maximum gas main pressure of about 6 inches W. C. If for some reason pressure in the gas main decreases below 6 inches W. C. valve 23 opens somewhat to relieve the pressure in pipe 19 and accordingly pressure on the underside of the motor 26 decreases causing opening of the valve 27 to permit propane to flow at a higher pressure.

Since the inspirator 50 is a large capacity inspirator, the regulator valve 25 and the pressure regulator valve 23 are so adjusted that the valve 27 will be throttled to such an extent that it will pass propane at about 10 pounds per square inch pressure. At this pressure the inspirator 50 will add sufficient air that the mixture discharging from this inspirator will have a B. t. u. content of approximately 800 per cubic foot. Of course, the inspirator 50 can be set to discharge the gas air mixture at any desired B. t. u. content. When the three inspirators 47, 48 and 49 are operating under 25 pounds pressure to produce approximately 800 B. t. u. gas air mixtures the inspirator

50 should be so adjusted as to produce a gas air mixture of the same heating value so that standby operation will be the same as normal operation.

At times when the demand on such a system is exceedingly great, I have made provision that inspirator 50 may be opened to the system to help satisfy the demand. The apparatus which permits simultaneous use of a large inspirator 50 is a pressure operated electrical switch 69. The pressure portion of this switch is connected by pipe 10 to the gas main 56. In operation when the inspirators 47, 48 and 49 are making gas and the pressure in the gas main decreases to a low value as for example, 4 to 5 inches W. C. this low pressure is transmitted through pipe 10 to the pressure operated switch 69 which causes the switch to open and break the electrical circuit flowing through wires 57 and 58. When this circuit is broken the solenoid valve 46 snaps open and propane at 25 pounds pressure then flows through inspirator 50 and into the gas main 56. Under such conditions pressure in the gas main soon increases to such an extent that the pressure operated electric switch 69 operates to close the circuit in wires 57 and 58 and close the solenoid operated valve 46.

As mentioned above, the inspirator 50, in one installation, was adjusted to produce an 800 B. t. u. gas air mixture at a propane pressure of 10 pounds per square inch and under this adjustment when propane flows through this inspirator at 25 pounds per square inch proportionately more air is drawn into the gas and the gas air mixture emerging has a lower B. t. u. content. In one case at a propane pressure of 25 pounds per square inch, I found that the B. t. u. content of the gas air mixture was 750 per cubic foot. While this B. t. u. content may be abnormally low, yet it will have only a small effect on the B. t. u. content of the gas air mixture in the main 56, since that issuing from inspirator 50 will be mixed with the mixtures issuing from the other three inspirators.

The same condition will exist at times of power failure when the standby inspirator 50 snaps into operation to replace the inspirators 47, 48 and 49. At the instant of change when inspirators 47, 48 and 49 close and inspirator 50 opens, propane will reach the latter inspirator at 25 pounds per square inch. This high pressure will cause the pressure in the gas main to increase rather quickly above 6 inches of W. C. and this increase in gas main pressure will be transmitted to the regulator valve 23, cause pressure in pipes 19 and 24 to increase and this increase accordingly operates the motor 26 to throttle the valve 27. This last operation takes place quite rapidly so that the large volume of propane at 25 pounds pressure passes through the inspirator 50 for only a very short time and accordingly the low B. t. u. gas air mixture from inspirator 50 is discharged and enters the main 56 only momentarily or for such a period of time until the motor valve 25 throttles to reduce the propane pressure reaching the inspirator 50. As soon as this propane pressure is cut to 10 pounds per square inch then the normal gas air mixture of 800 B. t. u. will be produced in the inspirator 50.

I have found that the switching from the inspirators 47, 48 and 49 to the standby inspirator 50 is so rapid and noiseless that an operator seldom knows that the change has been made. Of course, the change is made on account of the power failure, and when a power failure occurs

the operator should be warned in some manner. To furnish a warning under such conditions, I have shown in the drawing a signal assembly 11 which is intended to turn on a light or ring a bell or otherwise warn the operator that the electric power has failed and that the standby inspirator 50 is in operation. In case the signal assembly includes an electric light bulb or a bell, a battery should be provided to furnish electricity for this signal. The operation of this assembly is very simple and is such that when the current fails to flow in wires 57 and 58 for any reason whatever, a relay 11a operates to cause the battery circuit to ring a bell or light a light. And when the current starts to flow along wire 57, this relay 11a then operates to open the signal circuit to shut off the light or stop the ringing of the bell.

In the operation of the back pressure controller valve 23 and of the restricting orifice 20, the propane or other gas which flows through the small orifice 20 flows on through the valve 23 and into the gas main 56. Since the orifice 20 is very small and since the gas reaches the orifice at only 18 inches of water column pressure the amount flowing through the orifice 20 and regulator 23 into the main 56 is so small that it has little to no effect on the B. t. u. content of the gas in the main.

In the illustration given herein I have shown 30 a three inspirator system with one standby inspirator, but I do not wish to limit my invention to such a number of inspirators since it will be obvious to those skilled in the art that any number of inspirators of any desired capacity may be used. For example, if six inspirators are of the 35 type of inspirators 47, 48 and 49 then the pressure operated multiple controller switch 65 should have six control wires such as wires 60, 52 and 64 leading to the six inspirators. In like 40 manner, the number of standby inspirators may be more than one. For example, it may be desired to use two or three or more smaller inspirators in place of the large one which I have described.

45 Materials of construction may ordinarily be selected from those available on the market and suitable for the purpose at hand. In like manner, the solenoid control valves, the pressure operated multiple controller switch 65 and the zero governor 50 throttle valve assembly 25, the back pressure regulator 23 and the constant pressure outlet valves 4, 11 and 18, are all standard equipment and may be purchased from manufacturers or dealers.

55 It will be obvious to those skilled in the art that 55 various variations and alterations may be made in such a system as herein disclosed and yet remain within the intended spirit and scope of my invention. I wish to be limited not by the particular example given but only by the appended claims.

Having disclosed my invention, I claim:

1. In an electrically operated gas-air mixing system which is operable during times of electric power failure as well as during times when electric power is available, the combination of a source of liquefied gas under pressure, a first inspirator for mixing air with gas, a conduit for passage of gas from said source to said first inspirator, a gas main, a conduit for passage of mixed air and gas from said first inspirator to said gas main, a first electrically operated control valve for controlling the flow of gas from said source to said first inspirator, said electrically operated control valve adapted to open while

electric current is flowing to the electrical control of said valve and to close when current is not flowing thereto, a first pressure responsive control means adapted to control said first electrically operated control valve in response to gas main pressure, a second inspirator for mixing air with gas, a conduit for passage of gas from said source to said second inspirator, a conduit for passage of mixed air and gas from said second inspirator to said gas main, a second electrically operated control valve for controlling the flow of gas from said source to said second inspirator, said second electrically operated control valve adapted to close when electric current is flowing to the electrical control of said second valve and to open when current is not flowing thereto, a second pressure responsive control means adapted to control said second electrically operated control valve in response to gas main pressure and said first and second electrically operated control valves operated by electricity from a common source.

2. In an electrically operated gas-air mixing system which is operable during times of electric power failure as well as during times when electric power is available, the combination comprising a source of liquefied gas under pressure, a first inspirator means for mixing air with gas, a gas main, a first conduit for passage of mixed air and gas from said inspirator means to said main, a first conduit means for passage of gas from said source to said inspirator means, a pressure reducing means in said conduit means, said pressure reducing means in said conduit means responsive to pressure in said gas main, a first on-off electrically operated flow control valve in said conduit means, said first electrically operated flow-control valve adapted to remain open during such time as electric current is flowing to the electrical control of said flow-control valve and to close when current is not flowing thereto, a first pressure responsive control means adapted to control said first electrically operated control valve in response to gas main pressure, a second inspirator for mixing air with gas at a greater rate than said first inspirator means, a second conduit for passage of air-gas mixture from said second inspirator to said gas main, a second con-

duit means for passage of gas from said pressure reducing means in said first conduit means to said second inspirator, a second electrically operated on-off flow-control valve in said second conduit means, said second electrically operated flow-control valve adapted to remain closed during such time as electric current is flowing to the electrical control of said second flow-control valve and to open when current is not flowing thereto, a second pressure responsive control means adapted to control said second electrically operated on-off control valve in response to gas main pressure and said first and second electrically operated control valves operated by electricity from a common source.

3. The apparatus of claim 2 in which said first inspirator means includes a plurality of inspirators, said first on-off electrically operated flow-control valve includes a plurality of on-off electrically operated flow control valves, one each of said plurality of on-off electrically operated flow-control valves disposed in said conduit means to control flow of gas from said source to one each of said plurality of inspirators, and said plurality of on-off electrically operated flow control valves adapted to close and to open successively in response to successive changes of pressure in said gas main, and each of said plurality of valves adapted to close in case of electric power failure, and wherein said second electrically operated on-off flow control valve is responsive to pressure in said gas main and is adapted to open in case electric power is cut off therefrom.

4. The apparatus of claim 3 further characterized by an alarm means disposed operatively with said second electrically operated on-off flow control valve to indicate the opening of this valve.

DAVID W. SHAEFFER.
